UNITED STATES PATENT OFFICE.

OTTO G. HITCHCOCK, OF ERIE, PENNSYLVANIA, ASSIGNOR TO HAYS MANUFACTURING COMPANY, OF ERIE, PENNSYLVANIA, A CORPORATION OF PENNSYLVANIA.

LAUNDRY-TRAY FAUCET.

Application filed March 21, 1925. Serial No. 17,412.

To all whom it may concern:

Be it known that I, OTTO G. HITCHCOCK, a citizen of the United States, residing at Erie, county of Erie, State of Pennsylvania, have invented certain new and useful Improvements in Laundry-Tray Faucets, of which the following is a specification.

My invention relates to that class of devices known as laundry tray faucets, embodying the usual hot and cold water supply pipes, a common mixing chamber, and a swivel discharge pipe, adapting the device to be used in connection with a two-compartment laundry tub; and has for its object to provide an improved means for detachably attaching the device either to the rear wall of a tub, or to the wall of the room in proper relation.

20 In Letters Patent No. 1,496,756, granted June 3, 1924, to Hays Manufacturing Company, as my assignee, I have disclosed an improved faucet adapted for attachment to a laundry tub, and my present invention 25 preferably aims to utilize the same faucet casting as is disclosed in said patent.

In the accompanying drawing:—

Figure 1 is a front elevation of my improved device shown attached to the rear 30 wall of a conventional two-compartment laundry tub.

Figure 2 is a horizontal section taken on the line II—II of Figure 1.

Figure 3 is a side elevation of the device, 35 the rear wall of the tub being shown in section.

Figure 4 is a vertical sectional view showing the device attached to the wall of a room in proper relation to the tub.

40 Figure 5 is a front elevation of the U-bracket forming part of the attaching means.

Similar numerals of reference denote corresponding parts in the several views.

45 In the said drawing, the reference numeral 1 denotes a combination faucet as described above, the same being provided with the usual mixing chamber 2 for the hot and cold water, in the top of which is disposed 50 a swivel discharge pipe 3 adapted to discharge into either section of a two-compartment tub, in a manner readily understood. Formed integral with the bottom wall of the mixing chamber 2 are two lugs

4 each being apertured freely to receive a 55 threaded bolt 5.

To this extent the device preferably is identical with the faucet disclosed in my patent hereinbefore referred to. Said bolts 5 form means for detachably fastening to 60 the lugs 4 a bracket 6, substantially U-shaped, as shown in Figure 2, the ends of the forwardly projecting arms thereof being out-turned at 7 to register with the lugs 4, and said out-turned ends being threaded 65 to receive the inner ends of the bolts 5, whereby the parts may be firmly connected. The rear wall of this bracket 6 has a rounded depending portion 8, best seen in Figures 1 and 5, and is provided with a central 70 threaded aperture 9, and with a plurality of other smaller apertures 10, as shown. When it is desired to attach the device to a laundry tub having a straight wall, such as the ordinary slate laundry tub shown in Figures 1, 2 and 3, I provide a clamping plate 11 formed with a central boss 12, apertured to receive a screw bolt 13, the ends of said plate being down-turned at 14 to engage the inner wall of the tub, as seen in 75 Figures 1 and 3. To assemble the device, the faucet is disposed with respect to the tub in the position shown in Figure 1, with the arms 14 of the bracket 6 straddling the transverse partition 15 of the tub, and by 80 engaging the threaded end of the bolt 13 with the central threaded aperture 9 of the bracket 6, the upper edge of the tub may be clamped between the depending arms 14 of the plate 11 and the depending semi-circular portion 8 of the bracket 6, as clearly 85 shown in Figures 2 and 3.

Laundry tubs at the present time frequently are made of enamel, and are formed with rolled upper edges such as shown 90 in Figure 4, which are not adapted to receive the clamp hereinbefore described. In order to provide for the support of the faucet in proper relation to a tub of this character, it is necessary to attach the same to the wall of a room, to the rear of the tub, and this I accomplish by dispensing 95 with the plate 11, and by attaching the bracket 6 to the room wall by means of the screws 16 passing through the apertures 10 in said bracket. By this means the faucet 100 may be supported in proper relation to the tub, as readily will be understood.

While I have shown and described the bracket 6 as a separate element from the faucet proper, the same being attached thereto by the screw bolts 5, I wish it to be understood that the same may be cast integral with the faucet if so desired. By forming these parts separate, however, I am enabled to use with my present improvement the faucet casting disclosed in my patent hereinbefore referred to.

Having thus fully described my invention, what I claim as new and desire to secure by Letters Patent, is:

In combination with a laundry tray faucet, a clamping bracket fixed to the base of the same and comprising a downwardly extending apertured rear portion, a clamping plate formed with downwardly extending ends, and a screw bolt for drawing the two towards each other, said bracket being apertured to permit its attachment to a wall.

In testimony whereof I hereunto affix my signature.

OTTO G. HITCHCOCK.
